(57) **CLAIM**

The ornamental design for a conical dual-polarization horn antenna, as shown and described.

DESCRIPTION

FIG. 1 is a front view of a conical dual-polarization horn antenna design showing my new design.

FIG. 2 is a right side view of a conical dual-polarization horn antenna.

FIG. 3 is a left side view of a conical dual-polarization horn antenna.

FIG. 4 is a rear view of a conical dual-polarization horn antenna.

FIG. 5 is a bottom view of a conical dual-polarization horn antenna; and,

FIG. 6 is a top view of a conical dual-polarization horn antenna.

Any shading and cross-hatching are not features of the design but are utilized to illustrate the surface contours of the conical dual-polarization horn antenna design in the drawings.

The broken lines depict portions of the conical dual-polarization horn antenna that form no part of the claimed design.
